4 Claims. (Cl. 132—79)

This invention relates to a cosmetic carrier designed more particularly to receive a stick of mascara pigment, a brush for applying the same and a mirror.

The carrier consists of two separable parts, a pigment, brush and mirror holder and a casing therefor adapted to slide over the holder from one end thereof.

One suitable form of construction is illustrated, by way of example, in the accompanying drawing, wherein:

Fig. 1 is a side elevation of the casing;

Fig. 2 is a side elevation of the pigment, etc. holder; and

Fig. 3 is a section on the line 3—3 of Fig. 2.

As shown, the casing 5 is cylindrical in form and closed at one end. The holder 6 is of H-shaped cross-section and its peripheral parts are curved so as to fit the bore of the casing. At one end the holder has a disc-like end portion 7 of substantially the same diameter as the body of the casing. The purpose of giving the holder an H-shaped cross-section is to provide two longitudinal recesses 8 and 10 on opposite sides of the holder. One of these recesses, 8, receives the stick of mascara 9 and the other, 10, the brush 11 for applying the same. To aid in keeping the mascara and brush in their respective recesses the outer parts of the portions forming the sides of the H are inclined towards each other. The recesses are, therefore, of dovetail-type form. The device is provided also with a recess 12, the sides of which are inclined towards each other, adapted to receive a mirror 13. It will be noted that the generally circular form of the holder aids in making these recesses of dovetail-type form without making the sides thereof unduly thick and heavy.

Another dovetail-type recess 12 is provided along one side of the carrier to receive a mirror 13.

What I claim is:

1. A cosmetic carrier comprising an elongated member of H-cross-section having a disc-like terminal portion at one end and a casing closed at one end slidable over said member from the end thereof opposite said terminal portion.

2. A cosmetic carrier as in claim 1 in which one outer side of one of the portions forming the sides of the H is formed with a recess with bevelled edges to receive a mirror.

20 3. A cosmetic carrier as in claim 1 in which the outer parts of the portions forming the sides of the H are inclined toward each other to aid in retaining articles inserted between said portions.

4. A cosmetic carrier comprising an elongated 25 casing closed at one end and open at the other and a brush and pigment holder slidably mounted in said casing, said holder being of H-shaped cross-section with the facing walls of the side-portions of the H inclined towards each other to form dovetail-type longitudinal recesses to receive the brush and pigment.
